UNITED STATES PATENT OFFICE.

HENRY K. SHANCK, OF DAYTON, OHIO, ASSIGNOR OF ONE-FOURTH TO
JAMES A. SNELL, OF SAME PLACE.

TRICYCLE.

SPECIFICATION forming part of Letters Patent No. 289,151, dated November 27, 1883.

Application filed January 26, 1883. (No model.)

To all whom it may concern:

Be it known that I, HENRY K. SHANCK, of Dayton, in the county of Montgomery and State of Ohio, have invented a new and useful Improvement in Tricycles, of which the following is a full, clear, and exact description, reference being had to the annexed drawings, forming part of this specification.

This invention relates to tricycles, and the improvement consists of the novel construction hereinafter described and claimed.

In the drawings, Figure 1 is a vertical section of my improved tricycle. Fig. 2 is a rear elevation of the same, and Figs. 3, 4, 5, and 6 are detail views.

The frame-work of my improved tricycle consists of a pendent frame, A, mounted upon the axle B, and extended to the front and rear downward near the ground, and connected to the yoke C of the guide-wheel D by a goose-neck, E. The inclination of the goose-neck is to be such as to throw the handles F of the yoke within easy reach of the rider, who is to occupy a seat, G, arranged just above the axle on the frame A. At or near the rear extremity of the pendent frame A is a transverse stationary shaft, H, having a pair of pulleys, I I, loosely mounted thereon, and connected thereto by clock-springs J, arranged within the pulleys. To the pulleys I are connected cords K, which are adapted to be wound thereon by the action of the springs, and these cords are attached to the pulleys L L, respectively. To the pulleys L L are also attached cords M, M, which extend down in front of the axle, and are connected to the pedal-levers N N at points intermediate between the ends of the pedals. The pedals are to be loosely connected in any suitable manner to the shaft H. The pulleys L, which are mounted upon the axle B, are preferably to be made with spokes, and provided with two or more peripheral grooves, O O, of different diameters, and the cords M M are to be secured in perforations formed in the smaller grooves, and adapted to be laid over from the smaller to the larger grooves through recesses P, as shown in Fig. 4, when it is desired to increase the driving-power, as in heavy roads. The cords K are secured in the larger grooves O in like manner, and these

larger grooves are to be made wider than the smaller ones, in order to provide sufficient room for winding the two sets of cords thereon, when the cords M are placed in the larger grooves for the purpose above described. The pulleys L are to be provided with ratchets and pawls in the usual manner, and it is designed, also, that the wheels Q shall be provided with ratchets, to facilitate the turning of the vehicle around sharp curves.

It will be observed that instead of placing the clock-springs on the axle of the vehicle, in the usual manner, I locate them at the rear or pivoted end of the pedal-levers. The object of this construction is to adapt the machine to utilize the pressure or weight upon the pedals for exerting both an upward draft and pressure upon the rear of the frame A, so that the entire burden or weight of the rider on the vehicle shall be practically thrown forward, without special effort, to a position for acting upon the propelling apparatus, instead of resting squarely upon the axle. In this manner less muscular force is required for propelling the vehicle, since the weight of the rider is utilized in great measure for that purpose.

Instead of the two sets of cords, one set of continuous cords passing over the pulleys L and connecting the pedals with the pulleys I might be used, although I prefer the arrangement first described. If desired, also, additional clock-springs might be arranged in the pulleys on the axle.

On the yoke C are arranged springs R R, to break the jarring caused by the guide-wheel striking obstacles or uneven surfaces in the road. It is designed that a spring-cushion shall be used for the seat to assist in securing the same object.

S indicates the brake for the guide-wheel.

As shown in Fig. 6, the cords M are to be made of extra length and wrapped around the cross-bars T of the pedal-levers before being secured thereto, in order that they may be adjusted in length as occasion may require.

By constructing the tricycle as above described it is adapted for general use. The connection of the axle to the yoke of the guide-wheel by means of the low pendent frame and

goose-neck forms an open-sided vehicle, which is specially convenient for use by women, and as the weight of the rider may be easily thrown upon the propelling apparatus at will with but little, if any, change of position, the vehicle is adapted for use even by persons of but little physical strength.

What I claim is—

1. A tricycle having the pedal-levers pivoted to a frame projecting downward and rearward from the axle, and, in combination therewith, a pair of spring-actuated pulleys located on or near the pivot-rod of the pedal-levers, and having cords which are connected to pulleys on the axle and to the pedal-levers, substantially as shown and described.

2. A tricycle having the pedal-levers arranged with their free ends forward and the opposite ends pivoted to a frame projecting downward and rearward from the axle, and, in combination therewith, a pair of spring-actuated pulleys located on or near the pivot-rod of the pedal-levers, and having two sets of cords which are connected to pulleys on the axle and to the pedal-levers at points between the ends of the same, substantially as shown and described.

3. In a tricycle, the combination, with the main axle of the vehicle and the yoke of a front guide-wheel, of a connecting-frame projecting downward and rearward from the axle, and having a goose-neck adapted to incline the yoke toward the seat, a pair of pedal-levers pivoted to the lower part of said frame, the cord-retracting pulleys located on or near the pivot-rod of the levers, and the cords connected to pulleys on the axle and to the levers at points between the ends of the same, substantially as shown and described, and for the purpose set forth.

4. In a tricycle, the combination, with the axle and the two sets of driving-cords, of the pulleys having two or more peripheral grooves of different diameters, and recesses for passing the cords across from one groove to another, substantially as and for the purpose specified.

HENRY K. SHANCK.
